DEVICE FOR TRANSFORMING DIRECT CURRENT INTO ALTERNATING CURRENT OR VICE VERSA

Palle Niels Bendixen, Copenhagen, Denmark

Application February 8, 1946, Serial No. 646,387
In Denmark February 18, 1944

3 Claims. (Cl. 175—363)

1

This invention relates to devices for transforming direct current into alternating current or vice versa, said device having a vibrating member alternately connected with one or the other of two fixed contacts or sets of contacts.

In the devices of this type hitherto known, the vibrating member is provided with an armature attracted by an electro-magnet, the magnetizing coil of which is connected with a magnetizing switch adapted to be closed and opened through the vibrations of the armature, said armature thus acting as a self-braking automatic switch.

In such devices, a certain energy is required for maintaining the vibrating movements of the vibrating member, which energy is not made otherwise useful, and the efficiency of the device will, consequently, be rather small, especially at small loads. Further, the period of vibration is, in such devices, limited by the mass and rigidness of the vibrating member, and is thus unable to surpass a certain limit.

The invention has for its object to provide a device of the type referred to, in which these inconveniences are avoided, i. e. a device permitting of transformation of direct current into alternating current at high efficiency, even at small loads, and permitting of a very much shorter period of vibration than heretofore.

According to the invention, this object is obtained through the use of a piezo-electric crystal in the manner hereinafter set forth.

The invention will now be more fully described with references to the drawings in which

Fig. 1 schematically shows a piezo-electric crystal element for use in a device according to the invention, for explaining the operation of the crystal element.

Fig. 2 shows one form of a device according to the invention, and

Fig. 3 shows a modified form of the device.

The crystal element shown in Fig. 1 may consist of seignette salt, for example. The crystal element comprises two crystal plates *a* and *b*, between which is disposed an electrode *3*. On the sides of the crystal plates *a* and *b* remote from each other electrodes *1* and *2* are disposed which are connected together. As indicated in Fig. 1, the intermediate electrode *3* is connected with the positive terminal of a voltage source, whereas the outer electrodes *1* and *2* are connected with the negative terminal of said voltage source. Thus the outer electrodes will be negative, and the crystal element will bend as exaggeratedly shown in full lines.

By reversing the polarity of the voltage source,

2

the outer electrodes will be positive, and the crystal element will bend in the opposite direction, such as indicated in dotted lines.

The fact is made use of in the device shown in

5 Fig. 2. The crystal element, which is clamped between two blocks, is provided with a member *14* adapted to cooperate with two fixed contacts *16* and *18* and connected with the intermediate electrode *3*. At its end remote from this member the crystal is rigidly clamped between the clamping blocks *10* and *12*. The fixed contacts *16* and *18* are each connected with one terminal of a voltage source *20*, the middle *22* of which is connected through a switch *24* with the outer electrodes *1* and *2* and with the primary winding *26* of a transformer connected in parallel with a condenser *30* to the intermediate electrode *3*, the secondary winding of said transformer being connected with a consuming circuit.

10 The device described operates as follows:

When the switch *24* is closed, a current will flow through the transformer winding *26*, the intermediate electrode *3*, the member *14* and the fixed contact *16* to the negative pole of the voltage source *20*. Herby the electrodes of the crystal element are subjected to a direct voltage, the crystal element thereby bending itself so as to move the member *14* to contact with the fixed contact *18*. Now the direction of current is reversed, the current flowing from the positive pole of the battery over the contact *18*, the member *14*, the intermediate electrode *3* and the transformer winding to the middle *22* of the battery. Herby an opposed polarity is imposed on the electrodes the crystal element thereby bending itself back to the contact *16*. The direction of current in the transformer winding *26* being, thus, constantly reversed during the vibrations of the crystal element, an alternating voltage will be induced in the secondary winding *28* of said transformer.

15 The form shown in Fig. 3 differs from that shown in Fig. 2 in the outer electrodes *1* and *2* and the intermediate electrode *3*, respectively, being each connected with one end of the secondary winding *28* of the transformer.

20 Further, the contact member *14* of the crystal element is isolatedly fixed to the crystal element by means of an insulating layer *32*, and the voltage source *20* is inserted between the contact member *14* and the middle point of the primary winding *26*.

The device operates as follows:

25 When the switch *24* is closed, a current will flow through one half part of the transformer

winding 26 thereby inducing an opposed current in the secondary winding 28 which will cause the crystal element to bend itself to switch over the contact member 14. The further operation is like that described with reference to Fig. 2.

It will be understood that other modes of wiring are possible within the scope of the appended claims, it being only necessary that an alternating polarity is imposed on the electrodes of the crystal element during the vibrations of the same.

Even if the device in the foregoing is described as adapted to transform direct current into alternating current, it will be understood that it is also capable of performing the reversed operation.

What I claim is:

1. A device of the kind referred to, comprising a pair of opposed contacts, a contact member for alternatingly co-operating with said contacts, a piezo-electric crystal element composed of a pair of crystal members connected together, said crystal element carrying said contact member, an intermediate electrode disposed between said crystal members, outer electrodes disposed on the outer faces of said crystal members, and means controlled by said contact member and pair of contacts for imposing alternating voltage on said intermediate electrode and said outer electrodes.

2. A device of the kind referred to, comprising a pair of opposed contacts, connected with opposed ends of a direct voltage source, a contact member for alternatingly co-operating with said contacts, a piezo-electric crystal element composed of a pair of crystal members and carrying

said contact member, an intermediate electrode disposed between said crystal members and electrodes disposed on the outer faces of said crystal element and connected with an intermediate point of said voltage source, and a transformer, the primary coil of said transformer being connected at one end with said intermediate point of the voltage source and at the other end with said intermediate electrode.

3. A device of the kind referred to, comprising a pair of contact members connected with opposed ends of the primary coil of a transformer, a contact member for alternatingly co-operating with said contacts and connected with one end of a direct voltage source, said voltage source being connected at its other end with an intermediate point of said primary coil, a piezo-electric crystal element composed of a pair of crystal members and isolatedly carrying said contact member, an intermediate electrode disposed between said crystal members and connected with one end of the secondary coil of said transformer, and outer electrodes disposed on the outer faces of said crystal element and connected with the other end of said secondary coil.
